UNITED STATES PATENT OFFICE

159,188

TELEPHONE SET

Hiram D. Currier, Chicago, Ill., assignor to Leich
Electric Company, Genoa, Ill., a corporation of
Illinois

Application September 12, 1949, Serial No. 4,962

Term of patent 14 years

(Cl. D26—14)

To all whom it may concern:

Be it known that I, Hiram D. Currier, a citizen of the United States, residing at Chicago, in the county of Cook and State of Illinois, have invented a new, original, and ornamental Design for a Telephone Set, of which the following is a specification, reference being had to the accompanying drawings, forming a part thereof.

Fig. 1 is a top plan view of a telephone set, showing my new design as it appears when used as a desk set;

Fig. 2 is a side elevational view of Fig. 1;

Fig. 3 is a front elevational view thereof as it appears when used as a wall set; and

Fig. 4 is a side elevational view of Fig. 3.

I claim:

The ornamental design for a telephone set, as shown, and described.

HIRAM D. CURRIER.
